LATCH MECHANISM

Hal Raymond Linderfelt, West Los Angeles,
Calif., assignor to Douglas Aircraft Company,
Inc., a corporation of California

Application August 6, 1948, Serial No. 42,776

3 Claims. (Cl. 292—335)

1

The present invention relates to closures and doors and more particularly to improved mechanisms for the automatic locking against inadvertent operation of door latching mechanism in the open position of the door.

The present invention relates to improvements in mechanisms for locking a door or closure latching handle in the unlatched position of the latch bolt or bolts to thereby hold the same in their retracted positions within the door to prevent accidental or inadvertent movement of the handle to the position in which the latch bolt might be extended and damage or mar the door jamb in the event of the closure of the door. The present improvements are particularly adapted to aircraft doors of the flush or streamlined type in which a close and accurate fit of the door within its opening is desirable for aerodynamic reasons and particularly so in the event of sealed doors in pressurized or supercharged aircraft.

It is accordingly a principal object of the present invention to provide improved door latching and locking mechanisms. A further object resides in the provision of automatic means for preventing the extension of the latch bolts of a closure or door at such times when the door is in other than its closed position. Another object resides in the provision of relatively simple, yet positive-acting and foolproof mechanism for blocking the latching movement of the bolt of a door when the same is not in the closed position. Further objects of the present invention reside in improvements in the general arrangement and relationship of the interlocking mechanism with respect to the latching mechanism of a door, as well as in detailed improvements of the respective elements.

Other objects and advantages of the present invention will occur to those skilled in the art after reading the following description taken in conjunction with the accompanying drawings, forming a part hereof, in which:

Fig. 1 is an elevational view of a door to which the improved mechanism has been applied;

Fig. 2 is a detail view of the improved mechanism in the unlatched open position of the door;

Fig. 3 is a cross-sectional elevational view of the mechanism of Fig. 2 as taken along the lines 3—3 thereof;

Fig. 4 is a sectional plan view of the mechanism in both the open and closed positions of the door; and

Fig. 5 is a similar view of a portion of the mechanism of Fig. 2, in the latched closed position of the door.

Referring now to Fig. 1, the numeral 1 represents a wall or enclosure which may be the interior surface of the wall of an aircraft. This wall has an opening therein, as defined by the

2

jamb 28, within which there is disposed a closure or door 8, which door is preferably mounted upon the hinges 9 for movements between its opened and closed positions. The numeral 10 in Fig. 1 indicates the base plate or portion of a housing 18 for the improved mechanism of the present invention, which housing and mechanism is shown in greater detail in the remaining figures.

Referring more particularly to Figs. 2 and 3, it will be noted that the base plate 10 is rabbetted or recessed on its outer face to receive the outer sheet or skin of the door to which the flange of the base portion 10 is attached through its holes 13a, and the holes 8a of the door sheet, as by the rivets or other fastening means 11. A major portion of the improved mechanism is housed within the housing or cover 18 which is suitably bored, together with the base plate 10 and the cover sheets of the door, to rotatably support a handle shaft 12, having an internal handle 13 and an external handle 13a fixed to the inner and outer terminals thereof, respectively. A latch stop element 14 is fixedly attached to the shaft 12 in such manner that it rotates with the shaft as the handles 13 and 13a are manually rotated. This element 14 has an extended portion bifurcated at 14b to which the roller 15 is pivoted at 14c.

The handle assembly 12—13—14 etc. is resiliently held in either one of two alternate positions by means of a snap-action spring toggle rod 16 which is pivotally attached to the latch stop element 14 by means of the pivot pin 17. The toggle rod 16 is guided for reciprocation at its outer terminal through the apertured guide or pillow block 30, which in turn is pivotally mounted upon the shaft 31 for partial rotation or rocking within suitably bored portions formed in the base plate 10 and the housing cover 18. Inasmuch as the pivot 17 is eccentrically disposed with respect to the axis of the handle shaft 12 and the spring 29, which is sleeved upon the rod 16, is continually under compression, the pivot 17 is at all times urged away from the pivot shaft 31. Accordingly, as the handle shaft 12 is rotated past the dead centerline, joining the axes of shafts 12 and 31, the spring 29 in extending the distance between these pivots, causes the latch stop element 14, to which it is pivotally attached, to be quickly rotated to either of its alternate limit positions. By referring to Fig. 2, it will be seen that a stop portion 18a is integrally formed within the housing cover 18 and in this figure the latch stop element 14 has been rotated about shaft 12 as far as it can go in the counter-clockwise direction. This position of the toggle rod 16 and its pivotal connection 17 to the latch stop element 14 to the right of the handle shaft 12 corresponds to that in which the latching ele-

ments 40 (Fig. 1) of the door 8 are in their retracted or unlatched positions, as will be hereinafter more fully explained.

The latch stop element 14 is provided with a bifurcated portion 14b within which the roller 15 is mounted for rotation upon the pivot pin 14a. The roller 15 is positioned with respect to the axis of the handle shaft 12 such that in one of the said alternate or limit positions of the handle 13, the end of the projecting portion of the element 14 engages the above mentioned stop or detent 18a forming an integral part of the cover 18. In the other of said alternate limit positions of the handle 13, corresponding to the extended position of the latches 40, in which the door is latched to the jamb 28, the roller 15 will engage the other end of the same detent portion 18a, as shown in Fig. 5. The handle 13 can, however, only rotate the latching mechanism into this latched position of the door when the door is in the closed position, and the latch stop element 14 is freed or released by the automatic interlocking mechanism, and more particularly by the locking or blocking element 20, about to be described.

The blocking element 20 is pivotally mounted for rocking movements within the transverse plane of the roller 15, and that of the latch stop element 14 by which the roller is carried, being journaled at its pivotal terminals within the base plate 10 and the housing 18. The element 14 is provided with a detent or recess 14c into which the blocking element 20 is adapted to fit. This rockable lock member 20 extends through the cover 18 and is attached by the screw 19 to a lever 21. This lever 21 is pivotally connected to a push-pull rod 24 by means of the pivot pin 22 and is connected at its lower free terminal by the tension spring 23 to the internal stiffening channel 8b at the hooked spring terminal 23a; thereby tending to continually urge the lever 21 in the counter-clockwise direction into the position shown in Fig. 2. In this position the push-pull rod 24 extends toward the right, or toward the jam 28 of the door, and in this same position the locking element 20 is concurrently urged upwardly against the roller 15.

The spring 23 normally holds the locking element 20 in engagement with the detent 14a and against the roller 15 unless the tension of this spring is overcome by the automatic release means which is provided in the form of a bell crank lever 25, pivotally mounted at 25a upon the lug 8c of the door 8, the bell crank carrying at its outer terminal a pivoted roller 26. As more clearly shown in Fig. 4, the wall portion 7 is provided with a bevelled jam 28 which has formed thereon the cam or projection 27. This cam is engaged by the roller 26 as the door is moved from its full line open position A into the broken line closed position of the door as indicated at B. It will be noted that as the roller 26 strikes the end face of the cam 27 (as the door is closed) the bell crank member 25 is caused to be rotated in the counter-clockwise direction as viewed in the plan section of Fig. 4. The push-rod 24 is concurrently moved to the left causing the attached lever 21 to be rocked or moved into the position indicated by the construction lines in Fig. 5, in which the locking element 20 is rotated in the clockwise direction downwardly out of the path or orbit of the projecting portion of the latch stop element 14 and the roller 15.

The mechanism for actuating the bolts or latches 40 for the door is operated by means of

the cable drum 32 which is fixedly attached to the handle shaft 12 to rotate therewith. An endless cable 33 extends around the drum 32 as well as around a centrally disposed and somewhat larger diameter drum 34 pivotally mounted upon the pivot 35. Constructed and arranged to rock with the drum 34 are the bridle linkages 36 and 37 which are attached to push-pull cables or other flexible means 38 guided within the sheaths or tubes 39 and having attached at their outer terminals the latch bolts 40. It will accordingly be seen that as either handle 13, or 13a, is rotated the cable 33 causes concurrent rotation of the central drum 34, either pushing or pulling the flexible means 38 to extend or retract the latch bolts 40.

The operation of the door latching control mechanism and the automatic interlocking or blocking lock device is as follows:

With the door 8 in its closed position against the jamb 28 of the wall 7 the roller 26 is in the deflected position toward the door as shown in the broken line position B of Fig. 4 and the push-rod 24 and attached lever 21 are also moved toward the left causing the block 20 to be moved into the position shown in Fig. 5 out of the path of the projecting portion of the latch stop element 14 and the roller 15. Accordingly, in the closed and latched position of the door, the element 14 will be in the position shown in Fig. 5 and the position of the interlocking mechanism in the closed position of the door will be that shown in this same figure in which the block 20 is out of the path of the element 14 and the roller 15. In this closed and latched position of the door and its mechanism as shown in Fig. 5, it is possible to rotate the handle 13 (or the other handle 13a) downwardly or in the counter-clockwise direction in Fig. 5 until the projecting portion of the element 14 strikes the stop 18a, it being only necessary to overcome the compression in the spring 29 of the quick-acting toggle rod assembly 16. During this rotation of the handle shaft 12, the sheave or drum 32, and its engaged cable 33, cause rotation of the door control mechanism to thereby retract the latch bolts 40. The element 14 and the roller 15, when the latch bolts are fully retracted, assume the position shown in Fig. 2 with the aid of the toggle rod 16 and as the door is then pushed open and the roller 26 rolls off the end of the cam 27, the tension spring 23 causes the lever 21 to be rotated toward the right or in the clockwise direction as viewed in Figs. 2 and 5, and the blocking element 20 moves into the detent or recess 14c in the latch stop element 14, blocking any clockwise movement of the element 14, the roller 15 and the attached shaft 12. The door latch control mechanism is therefore locked in its unlatched condition as long as the door is in any other than its fully closed position as determined by the engagement or disengagement of the roller 26 and the cam element 27 on the jamb 28. Accordingly, it is not possible to close the door with the latch bolts 40 in their extended positions.

Other forms and modifications of the present invention both in respect to its general arrangement and the details of its respective parts, which may become apparent to those skilled in the art after reading this description, are all intended to fall within the scope and spirit of the present invention as more particularly defined in the appended claims.

I claim:

1. Latch mechanism for a door comprising a manually rotatable latch operating means, a bell-crank lever pivotally mounted upon the door upon an axis substantially parallel to the plane of said door, a first arm of said bell-crank lever rotatable into a block position in which it prevents manual operation of said latch operating means, resilient means attached to said bell-crank lever urging said first arm portion into said blocking position, stop means fixedly carried by said door for engagement by said manually rotatable latch operating means for defining the extreme limits of movement thereof, spring-pressed toggle means pivotally interconnecting said manually rotatable latch operating means with said door for snap-action movement of said manually rotatable latch operating means into either of said limit positions whenever manually rotated past an intermediate position and released at such position, and jamb engaging means including a pivotally mounted roller operatively carried by a second arm of said bell-crank lever arranged in such manner that in the closed position of said door, said jamb engaging means imparts rotation to said bell-crank lever thereby overcoming said resilient means and rotating said bell-crank lever into the unblocking position of said first arm portion in which said latch operating means is free to be manually actuated into either its latch extended or latch retracted limit position.

2. Automatic latch blocking means for a door installation including a hingedly mounted door and a wall having a jamb portion defining an opening arranged to be closed by said door, comprising bolt means movably mounted upon said door for latching engagement with said jamb portion, manually rotatable actuating means operatively connected to said bolt means for the extension and retraction of said bolt means, a projecting portion carried by said rotatable bolt actuating means, stop means fixedly carried by said door for engagement by said projecting portion at the extreme limit positions of retraction and extension movements of said rotatable bolt actuating means, spring-pressed toggle means pivotally interconnecting said rotatable actuating means with said door for snap-action movement of said rotatable bolt actuating means into either of said limit positions, blocking means operatively engageable with said rotatable bolt means for blocking the rotation thereof, strike

means fixedly carried by said jamb portion, a bell-crank lever pivotally mounted upon said door on an axis substantially parallel to the plane of said adjacent door surface, said bell-crank lever pivotally connected to said blocking means and having a portion in engagement with said strike means arranged in such manner that upon closing of said door and engagement of said bell-crank lever with said strike means rotation is imparted to said bell-crank lever causing movement of said blocking means into a position in which said manually rotatable bolt means is free for manual rotation into either one of said limit positions in which said bolt means may be extended or retracted.

3. Latch mechanism for a door installation including bolt means for latching said door to its jamb, manually rotatable means for operating said bolt means into either its extended or its retracted limit positions, spring-biased toggle means operatively connected to said manually rotatable means for rotating said manually rotatable means into either one of said two limit positions upon release of said manually rotatable means, blocking means operatively engaging said manually rotatable means for blocking the rotation thereof, strike means carried by said door jamb, a bell-crank lever pivotally mounted upon said door upon an axis substantially parallel to the surface of said door, said bell-crank lever pivotally connected to said blocking means and having a contacting portion engageable upon closing of said door with said strike means carried by said door jamb arranged in such manner that said bell-crank is rotated thereby imparting movement to said blocking means for the freeing of said manually rotatable means in such manner that said bolt means may be extended or retracted manually in said closed position of said door.
